UNITED STATES PATENT OFFICE.

JULIUS TERBERGER, OF HILFARTH, GERMANY.

MACHINE FOR PEELING WILLOW AND LIKE MATERIAL.

Application filed May 3, 1926, Serial No. 106,483, and in Germany May 6, 1925.

This invention relates to a machine for peeling willow and like material in which the rod to be peeled is pulled through a spring-influenced stripper by means of a 5 clamp arranged on a revolving wheel and adapted to be automatically closed and opened for gripping or releasing the rod.

There has already been proposed a machine of this type in which the clamp which 10 seizes the rod at a point ahead of the stripper, is designed to introduce it into and pull it through the stripper which consists of a spring bow with overlapping blades at its 15 ends. However, the purpose striven for cannot be attained with this known machine. For introducing the rod into the stripper of this machine the rod ought to overcome the 20 spring force of the spring bow of the stripper, but it will not do this because of its own flexibility; therefore the rod will not open the stripper but simply glide along the same without being peeled. Besides, if 25 one would tend to aid in the introduction of the rod into the stripper by hand, the introduction could only be effected in the known machine after the thick end of the rod would have moved already for a considerable 30 distance beyond the stripper, because only at such a point the rod would assume the angular position required for engaging the 35 stripper, since the latter is arranged outside the path of the clamp. Therefore the most valuable thick end of the rod would not be peeled. Another drawback of the known 40 machine resides in that the stripper is never positively opened so that it will soon be clogged up with the bark or skin stripped from the willow rods which will interfere with the proper working until it has been 45 removed from the stripper by hand. This drawback is even aggravated by the oblique position of the stripper in the known machine.

All of these disadvantages are avoided by 50 the machine according to the invention, in which the thick end of the willow rod is inserted into the stripper and seized by the clamp after the latter has passed the stripper so that the rod is pulled through the stripper throughout its entire length. This is attained by arranging the stripper in 55 the path of movement of the clamp, causing the clamp which is carried by a wheel to pass over the stripper in open condition and to close immediately in rear of the stripper for seizing the thick end of the rod to be

peeled held in the stripper. The stripper is prevented from being clogged with the stripped-off bark by positively opening and closing the stripper at each revolution of 60 the clamp-carrying wheel to such an extent that all bark remaining between the stripper jaws may drop out. This is still facilitated by arranging the stripper with its mouth directed vertically downwards. 65

Another object of the invention is to make the stripper jaws of round iron bars so as to prevent them from injuring the wood.

A further object of the invention consists in making the stripper of a construction so 70 that its pressure on the rods to be peeled may be regulated in a simple and quick manner in accordance with the softness of the material to be treated.

Still other objects of the invention reside 75 in the construction and arrangement of the means for automatically opening and closing the clamp and the stripper during the operation of the machine.

An embodiment of the subject-matter of 80 the invention is illustrated, by way of example, in the accompanying drawing in which:

Fig. 1 is a side elevation of the machine with the clamp in a position in which it has 85 moved beyond the stripper;

Fig. 2 is a front elevation thereof with the clamp immediately in front of the stripper;

Fig. 3 is a detail front view of the stripper on an enlarged scale, and 90

Fig. 4 is a bottom plan view of Fig. 3.

The machine comprises a stationary stripper *a* and a revolving clamp *i*. The stripper *a* is mounted on a pin *g* of a transverse bar of the frame *q* of the machine, while the 95 clamp *i* is carried by the circumference of a revolving wheel *s* which is fastened on the driving shaft *r* mounted in the frame *q*. The stripper *a* is arranged in the path of movement of the clamp *i*. Both the stripper 100 and the clamp are constructed as tongs. The mouth opening of the stripper lies vertically downwards. The opening and closing of the stripper *a* is effected by means of cam disks *f* which are fastened on the shaft *r* so that 105 they take part in the rotation of this shaft. The clamp *i* is opened and closed by means of cam disks *l* through which the shaft *r* passes freely and which are rigidly connected with the frame *q* by brackets *q'*. Connected 110 with the free ends of the shanks *b* of the tongs which form the stripper *a* and which

are pivoted on the pin g , are helical springs h which tend to close the stripper. The other ends of the springs h are connected with set screws h' held by means of wing nuts in brackets g'' of the frame q . The tension of the springs h and the consequent pressure of the stripper a on the rods or stems inserted into it may be regulated by adjusting the screws h' . The shanks b of the stripper a have besides pivotally connected with them transmission rods c , the other ends of which are pivoted to levers d which are rotatably supported at e on the frame q . These levers are placed under the action of the cams f . Once at each revolution of the shaft r , the levers d are depressed by the cams f so as to open the stripper a through the intermediary of the rods c against the action of the springs h . Upon the action of the cams f on the levers d having ceased, the stripper is immediately closed again and the levers d are returned into their initial positions by the springs h .

The shanks i' of the tongs forming the clamp i are pivotally connected with shifting rods k , movable in guides s of the wheel s and provided at their free ends with heads m . These heads are held in contact with the circumference of the cam disks l by means of helical springs n the one ends of which are connected with the rods k , while their other ends are adjustably connected with toothed bars o arranged on the body of the wheel s . As will be understood, the springs n tend to close the clamp i . By connecting the springs n to one or the other tooth of the bars o the tension of the springs n and consequently the clamping pressure of the clamp i may be regulated. The cam faces of the disks l are adapted to shift the rods k against the action of the springs n in such a manner that the clamp i is opened. The cam faces are of a configuration so that the rods k are instantaneously returned to their initial positions and the clamp i is closed through the action of the springs n as soon as the rods k have passed beyond the portion of the cams which has the greatest diameter and at which the clamp is in wide open condition. To this end, the highest point of each cam face is connected with its lowest point by a radial face as may be clearly seen from Fig. 1. The machine is preferably driven by means of an electromotor.

As more particularly shown in Figs. 3 and 4, the jaws of the stripper a consist of horizontal arms a' attached to the shanks b and having at their free ends vertically depending bars a'' of round section which are preferably covered with rubber. The arms a', a'' and the bars a'', a'' are usually in contact with each other under the action of the springs h . The horizontal arms a' are provided on their top surfaces with plates a''' outwardly inclined in upward direction.

These plates are designed to have placed between them the thick end of the willow rods to be peeled. When the stripper is opened the willow rod will drop between the bars a'' and be seized by the same when the stripper is closed again. The stripper is always opened only for a very short moment so that there is no time for the willow rod to fall entirely through the stripper when same is being opened. 75

As indicated in dotted lines in Fig. 1, there may be arranged at the front side of the machine a table p on which the rods to be peeled are piled and from which they are manually fed to the stripper of the machine. 80

The operation of the machine is as follows: The machine is started and a willow rod is taken from the table p and placed with its thick end between the guide plates a''' so that it rests on the horizontal arms a' . 85 During the rotation of the shaft r the jaws a', a'' of the stripper a are moved apart so that the rod resting on the arms a' drops between the bars a'' and is seized by the same inasmuch as the stripper is closed again by the springs h immediately upon having been opened. When the clamp i carried by the wheel s reaches the point A it has been widely opened by the cams l and in this open condition moves past the stripper a as is to be seen from Fig. 2. When the clamp i reaches the point B it has already closed and seized the thick end of the rod held in and projecting from the jaw bars a'' of the stripper a in the direction of movement of the clamp i . 90 During the further movement of the clamp i , same pulls the willow rod through the stripper a so that the bark or skin is stripped from the rod. When the clamp i comes into its lowermost position, it begins to open again so that the peeled rod is released and drops to the bottom. When the stripper a is opened the bark contained therein falls out of it before the next rod drops between and is seized by the jaws of the stripper. 95 100

Having thus described my invention, what I claim as new and desire to secure by Letters Patent, is:—

1. A machine of the character described, comprising a rotary wheel provided with a clamp on its circumference, a stripper mounted on the frame of the machine in the path of movement of the said clamp, means for opening and closing the stripper so as to allow it to receive and hold one end of the rod to be peeled, means for opening the clamp during its movement past the stripper and for closing it immediately upon having passed beyond the stripper so that it will seize the rod end held in the stripper and pull the rod through the stripper during the further movement of the clamp-carrying wheel. 115 120 125

2. A machine of the character described, comprising a rotary wheel provided with a 130

clamp on its circumference, a stripper mounted on the frame of the machine in the path of movement of the said clamp and consisting of tongs having jaws including horizontal arms with guide plates on their top surfaces and gripping bars of circular cross-section vertically depending from the free ends of the horizontal arms, means for opening and closing the stripper so as to allow it to receive and hold one end of the rod to be peeled, means for opening the clamp during its movement past the stripper and for closing it immediately upon having passed beyond the stripper so that it will seize the rod end held in the stripper and pull the rod through the stripper.

3. A peeling machine, comprising a rotary wheel carrying a pulling clamp on its circumference, a stripper in the form of tongs mounted on the frame of the machine in the path of movement of the said clamp, springs operatively connected with the shanks of the stripper tongs for keeping the stripper closed, setting screws connected with the springs and adapted to regulate their tension, means for opening the stripper against the action of the springs, and means for opening the clamp during its movement past the stripper and for closing it immediately upon having passed beyond the stripper so that it will seize the rod end held in the stripper and pull the rod through the stripper.

4. A peeling machine, comprising a driving shaft mounted in the frame of the machine, a wheel fastened on the driving shaft and carrying a pulling clamp on its circumference, a stripper in the form of tongs mounted on the frame in the path of movement of the said clamp, springs operatively connected with the shanks of the stripper

tongs for keeping the stripper closed, means for regulating the tension of these springs, levers mounted on the frame, connecting rods between the levers and the shanks of the stripper tongs, cams fixed on the driving shaft and adapted to rock the said levers so as to open the stripper against the action of the springs connected therewith, means for opening the clamp during its movement past the stripper and for closing it immediately upon having moved past the stripper.

5. A peeling machine, comprising a driving shaft mounted for rotation in the frame of the machine, a wheel fastened on the driving shaft and carrying on its circumference a pulling clamp in the form of tongs, a stripper mounted on the frame in the path of movement of the clamp, means for opening and closing the stripper so as to allow it to receive and hold the rod to be peeled, shifting rods connected with the shanks of the clamp tongs and arranged to slide radially in guides fixed on the wheel, cams loosely mounted on the driving shaft and rigidly connected with the frame, said cams being arranged for cooperation with the free ends of the shifting rods and adapted to open the clamp through the intermediary of the said shifting rods when the clamp moves past the stripper, springs connected with the shifting rods and the wheel and adapted to close the clamp and hold it closed immediately upon the clamp having moved past the stripper, so that the clamp will grip the rod to be peeled held in the stripper and pull it through the latter.

In testimony whereof I have signed my name to this specification.

JULIUS TERBERGER.
